UNITED STATES PATENT OFFICE.

LEO MONTEL, OF NEW YORK, N. Y.

ACETYLENE-GAS GENERATOR.

SPECIFICATION forming part of Letters Patent No. 761,386, dated May 31, 1904.

Application filed April 3, 1903. Serial No. 150,912. (No model.)

To all whom it may concern:

Be it known that I, LEO MONTEL, a citizen of the United States, residing in the borough of Manhattan, in the city, county, and State of New York, have invented certain new and useful Improvements in Acetylene-Gas Generators, of which the following is a specification, reference being had to the accompanying drawings, forming a part hereof.

This invention relates to acetylene-gas generators; and its general object is to provide a safe and convenient generator of this class for use in portable lamps, such as table-lamps, and also to provide an acetylene-lamp which shall be suitable for family use. In lamps wherein acetylene is generated and burned it is difficult to provide for the entrance of a proper amount of atmosphere to compensate the varying pressure in the interior of the lamp and to provide for the uninterrupted feeding of water to the carbid and at the same time to prevent the occasional backing out of the water through the opening provided for the entrance of air.

Accordingly one object of this invention is to provide a valve which shall permit the proper inflow of air into the interior of the lamp, but which will prevent the outflow of any water or gas therethrough at all times, and even though the lamp be upset.

Another object of the invention is the provision of an improved controlling-cock to control the supply of gas to the burner and of air to the interior of the lamp, which cock is to be operated in connection with a raising and lowering device for the carbid, with which the invention is also concerned.

Still another object of the invention is the provision of a safety device for closing the carbid-container chamber to prevent the entrance of water therein when the lamp becomes upset for any reason, and, lastly, one other object of the invention is to furnish a handy and efficient means for securing quickly and tightly the top of the lamp upon the outer or inclosing body of the lamp when the shell is introduced into the body.

In the accompanying drawings, Figure 1 is a central vertical section of a lamp embodying the invention. Fig. 2 is a horizontal section

taken through the shell on a plane indicated by the line $\alpha\alpha$ in Fig. 1, the carbid-container, with the grate and closing-plug, being removed. Fig. 3 is a detail view, in vertical section, of a safety device which has been sprung to force the plug into the end of the carbid-container chamber. Figs. 4 and 5 are detail views in elevation illustrating the construction of the closing-catch. Figs. 6 and 7 are detail-views, partly in section, of a blow-off valve. Fig. 8 is a horizontal section taken through the lamp on a plane indicated by the line $\beta\beta$ in Fig. 1. Fig. 9 is a detail view, in vertical section, taken on a plane indicated by the line $\gamma\gamma$ in Fig. 1. Figs. 10 and 12 are detail views in elevation, and Fig. 11 is a detail plan view, of the valve for controlling the flow of gas to the burner and the flow of air to the interior of the lamp. Fig. 13 is a detail view in elevation of the connections between the lifting-rod and the handle of the controlling-cock.

The outer or inclosing body 1 of the generator may be shaped to form a lamp-body and is of sufficient size to serve as a container for the water and to receive the shell 2 forming the generating-chamber 2^a and secured to the upper part 6 of the lamp by the carbid-container 3 and the partitions 4 and 5. In order to attach quickly and conveniently the upper part and shell of the lamp to the lower part or body and at the same time to insure a perfectly tight joint between the two parts, a longitudinally-slidable catch 19 is provided, Figs. 1, 4, and 5, a small space being isolated from the main or water chamber 1^a by a partition 19^a for said catch to work in. On the upper end of the catch is a nose 22, adapted to engage a projection 31, Fig. 8, on the top 6, and in the lower part of the catch is a square opening 20, the sides of which are engaged by a cam 18, secured to or made integral with a short shaft 17, having a squared portion which enters one of the lamp-handles 10, the cam being provided with a retaining-bushing 21, fastened in the sides of the body and serving also as a bearing for shaft 17. The lower end of the handle 10 is provided with a suitable latch 11, by which it may be disengaged from the lamp-body and tilted, thereby turning the

cam and causing the catch 19 to be raised to disengage the top. The handle of the lamp thus serves as a lever for operating catch 19. A rubber gasket 26 is provided between the body and the shell to make a tight joint, and as soon as the catch 19 is raised the shell or top is turned slightly in a left-handed direction to disengage it from a stop 23 and the catch 19, Fig. 8, when it may be lifted from off the body. The projections 31 are provided with shoulders 32, which act as stops when the top is being secured in the body by turning it in a right-handed direction.

Between the partitions 4 and 5 a gas-receiving chamber 4^a is formed, which communicates with the generating-chamber through a tube 4^b, said receiving-chamber in turn communicating with a chamber 5^a, connected with the burner 8 by a passage 58 59. This passage is provided with a cock 52, having a stem 56, a seat 55, and a controlling-handle 57, said cock being provided to regulate and control the supply of gas to the burner. For this purpose the stem of said cock is cut away near one end to form a channel between itself and its seat, by which channel communication may be established and regulated between the two ends of the passage 58 59 and by which therefore communication between the chambers 4^a and 5^a may be fully or partially established or wholly cut off, as may be desired. Said cock is also provided with a second channel 61, communicating with the outer air, which channel when the cock is opened to establish full communication between the chamber 4^a and the chamber 5^a registers with an air-passage 60, communicating with the water container or chamber 1^a. Furthermore, the relation between the channels of the cock is such that when there is only partial communication between the chambers 4^a and 5^a or when communication between said chambers is wholly cut off communication between passage 60 and the outer air will be wholly cut off. In said passage there is provided a valve-seat 63, having openings 67 through which it communicates with the water-chamber, and within said valve-seat is a plug having a cork body 64 and a rubber head 65, said plug being there-by adapted to float and close the passage 60 should any water back out from the water-chamber into the valve-seat owing to a sudden pressure in the generating-chamber or to any other cause. Said plug rests upon a heavy metallic ball 68, which in case the lamp is upset will force the plug against the opening in the passage 60, and thereby prevent the escape of water from the generating-chamber 1^a, which in such a case would tend to flow out through the same.

Connected with handle 57 of the cock 56, preferably by a cam-and-pin connection, is a raising and lowering device for the carbide-supporting grate 36. The connections between the handle 57 and the raising and lower-

ing device are such that when the handle is moved to permit communication to be established between the chambers 4^a and 5^a the grate will be lowered to bring the carbide in contact with the water in the generating-chamber and that when said handle is turned to cut off communication between the chambers 4^a and 5^a the grate and carbide will be raised out of the water. For this purpose said device comprises a lifting-rod 49, which works in a suitable guide-tube 50. The upper end of the rod 49 has a cross-bar 90 secured thereto, and a cam 91, which is secured to the cock, bears against said cross-bar and serves, when the handle 57 is turned, to raise or lower the rod 49, according to the direction in which the handle is moved. A guide 92 is provided upon the exterior of the lamp-body upon which the bar 90 travels to prevent the rod 49 from turning while being moved, the lower end of said guide being provided with a suitable packing device 51, a yoke 45, pivoted at 48 to the shell 2, a connection 47 between the end of the rod 49 and the yoke, and a curved cross-bar 44, pivoted in the yoke. When the lamp is in operation, these parts remain in the position shown in Figs. 1, 2, and 3, and when the generation of gas is to be stopped the rod 49 is lifted by the proper movement of the handle 57 and raises the yoke 45, which brings the curved portion of the cross-bar 44 against the lower portion of the grate-support and raises the latter. While the curved bar 44 is in the position shown in Fig. 2 the ends 46 of said bar, which are turned in to engage the upper sides of the yoke 45, lock or prevent the curved portion 44 from being turned out of the path of the grate-support. When, however, it is desired to remove from or insert in the carbide-container 3 the grate and the carbide, said rod may be turned up and over, so as to bring the curved part 44 out of the path of the grate, which is then easily removed or inserted, as the case may be.

Figs. 10, 12, and 13 show the position of handle 57 and the parts adjacent thereto when the carbide is in its lowest position and the cock is open to its fullest extent. When the handle 57 is turned so as to establish only a slight communication between chambers 4^a and 5^a through the cock, the position of said handle is shown in the dotted lines in Fig. 12. In such a position the weight of the carbide transmitted through the rod 49 to cam 91 would cause the cock to swing around to its full-open position unless some means were provided to check such movement. Accordingly a dog 86 is pivoted upon the exterior of the lamp adjacent to the cock, Figs. 10 and 12, which dog when the handle is in the position shown in dotted lines in Fig. 12 drops into a recess portion 93 of the casing and prevents the carbide from causing the handle 57 to swing around to bring the cock to its full-open position.

The carbide is furnished to the lamp preferably in the form of cylindrical cartridges 43, and for conveniently holding the carbide a tube 33 is provided and supported upon the grate 36, which tube is slightly smaller than the carbide-container tube 3, in which it may move freely in a vertical direction when the lamp is placed in operation or when the generation of gas is stopped. In order to prevent the entrance of the water within the carbide-container chamber when the lamp is tipped over, a safety device is provided to close the lower end of said chamber. For this purpose a plug 40, having a rubber washer 41, is secured to the lower end of the grate by suitable means, such as fasteners 39, said plug being of a conical shape and of a size adapted to fit within the lower end of the tube 3. Said plug is provided with a rod 42, having a head 42^a, against which any suitable automatic closing device may act. Such a closing device preferably comprises a lever 79, bent to prevent it from interfering in its movement with the lifting device and pivoted on a standard 25 80, said lever being engaged by a vertically-moving frame 78, rigidly secured to a rod 76. The frame is also formed in such a way as to prevent it from interfering in its movements with the lifting device and also with the lever 79. Such closing device further comprises a free disk 69, which lies between the bottom of the lamp and the support upon which the lamp happens to rest, a spring 75 being confined between the disk 69 and the lamp-bottom, whereby the disk 69 tends to move away from the lamp-bottom and draw with it the rod 76, but is prevented from so doing so long as the lamp rests firmly upon its bottom. In case, however, the lamp becomes tilted or upset the closing device is sprung, the disk 69 drawing away from the bottom, together with the rod 76, and causing, as illustrated in Fig. 3, the downward movement of the frame 78, which drives the plug 40 forcibly into its seat in the lower end of tube 3. A recess 70 is provided in the bottom of the lamp, which is engaged by a circular projection upon the disk 69 to prevent the entrance of any matter between the disk and the lamp and also to prevent the displacement of the disk. A packing-ring 72 is provided around the rod 76, and a steel washer 73 is also provided to receive the thrust of the spring 75.

It will be clear that instead of providing a plug adapted to move and close the carbide-container in order to seal the same against the entrance of water when the lamp is upset any other means for preventing the water from coming in contact with the carbide may be employed. For example, in a generator where the parts are arranged as in the present case a valve in the container-tube may be employed instead of the plug, or the tube itself may be moved to effect the closing thereof.

Accordingly the invention is not limited to

any particular means of closing the carbide-container for this purpose. Moreover, the closing device actuating or effecting the operation of the closing means is capable of being constructed in various ways. The spring 75, 70 for example, may be arranged within the generator and the spring may be normally extended by a tensile force instead of being normally compressed, as in the present case, or some other similar device may be substituted 75 for the spring. Furthermore, the connections between the spring and the closing means may be changed, and the disk may become a mere point, the one essential being that there shall be means upon the exterior of the lamp which 80 the weight of the lamp shall normally hold in check, but which are disengaged when the lamp is tilted or upset, thereby setting free a spring or some other source of energy to operate means for closing the carbide-container. 85

When the upper portion of the lamp is placed within the lower portion or body of the lamp, the air which would naturally be confined in the generating-chamber 2^a is permitted to escape to a certain extent through 90 a blow-off valve 83, Figs. 6 and 7, which is controlled by a cock 82 and connects with a pipe 12. The distance of the lower end of pipe 12 from the bottom of chamber 2^a, it will be seen, will determine the quantity of air 95 which is permitted to escape through said pipe as the upper portion of the lamp is inserted in the lower portion, for as soon as the lower end of said pipe comes in contact with the water in the body 1 said pipe will be sealed 100 and no more air will escape. The length of said pipe is such as to permit just enough air to escape to allow the water in the chamber 2^a to rise approximately as high as the lower end of the tube 3 when the two portions of 105 the lamp are secured together. Said cock is provided with a controlling-lever 84 85, which has a hooked portion 84 and a straight portion 85. When the upper portion of the lamp is placed in the lower portion, the lever and valve are in the position shown in Fig. 6, the valve being open; but when the position indicated at Fig. 6 is reached the hooked portion 84 of the lever engages the top of the lamp-body and closes the valve, the closed position 110 being indicated in Fig. 7. The valve remains in this position until the upper part of the lamp is removed from the body, when the straight portion of the lever 85 engages the under side of the top of the lamp-bottom and 115 opens the valve 83.

When the generator has been standing for any length of time—as over night, for instance—a slight pressure may develop therein, owing to the after generation of gas which 125 is liable to occur so long as the carbide remains wet. Accordingly when the lamp is to be lighted under these conditions the cock 52 is only partially opened to establish only a slight communication between the chambers 4^a and 130

5^a, the air-inlet opening, as was explained, not being opened thereby. The lamp now being lighted, as soon as the interior pressure has worked off the flame will go down, and the 5 cock is then turned to establish full communication between the chambers 4^a and 5^a, whereby the air-inlet will be opened and the carbid lowered into the water. The water, which is introduced into the chamber before 10 the top of the lamp is placed upon the body of the lamp, will when the two parts of the lamp are brought together in their proper relation be forced nearly to the top of chamber 1^a. The blow-off valve 83 will permit a sufficient quantity of air to be discharged from 15 the generating-chamber 2^a to permit the water to rise in said chamber a little above the bottom of tube 12. The opening of cock 52 will allow the air which is confined in the generating-chamber to escape and at the same time will permit the lowering of the water in the water-container, which rises and fills the place occupied by the discharged air. When 20 the handle 57 is moved to open cock 52, the carbid is at the same time lowered, so that the lower portion of the carbid projects outside the container-tube 3. The water continues 25 to rise in the generating-chamber until it reaches the carbid, when the generation of gas will at once commence and the further rise 30 of the water will be stopped. Finally, an equilibrium will be established between the pressure of the gas in the generating-chamber and the pressure of the column of water in the water-container, the degree of this pressure determining the pressure of the gas at the burner. This equilibrium between the pressure of the 35 gas in the generating-chamber and the pressure of the column of water in the container 40 will be maintained until the carbid is exhausted and the generation of gas ceases.

It will be obvious that while my invention 45 comprises certain details relating to the construction and operation of acetylene-generators it is by no means limited to the precise details shown and described hereinbefore; but it is capable of different embodiments, of which the present embodiment is considered preferable. Accordingly the invention is not limited 50 to the precise construction shown and described.

I claim as my invention—

1. In an acetylene-gas generator, the combination of a body, a shell, a catch within the 55 body to secure the shell to the body, a handle upon the body, and connections between the handle and the catch whereby the latter is controlled by the handle.

2. In an acetylene-gas generator, the combination of a body, a shell, a catch within the 60 body to secure the shell to the body, a gasket between the shell and the body, a handle upon the body, and connections between the handle and the catch whereby the latter is controlled 65 by the handle.

3. In an acetylene-gas generator, the combination of a body, a shell, a catch within the body to secure the shell to the body, a handle upon the body, connections between the handle and the catch whereby the latter is controlled by the handle, and a latch upon the handle to secure the handle to the body. 70

4. In an acetylene-gas generator, the combination with a body and shell, of a catch comprising a sliding member within the body, a 75 cam engaging said member, and a handle upon the body operatively connected with the cam whereby the movement of the handle effects the operation of the catch.

5. In an acetylene-gas generator, the combination with a body, a handle upon the body and a shell, of a catch within the body comprising a sliding member, a cam engaging said member, and rigid connections between said cam and handle, whereby the movement 85 of the handle effects the operation of the catch.

6. In an acetylene-gas generator, the combination with a body, a handle upon the body and a shell, of a catch within the body comprising a sliding member with a square hole 90 therein, an L-shaped cam within said hole, and rigid connections between cam and handle, whereby the movement of the handle effects the operation of the catch.

7. In an acetylene-gas generator, the combination with the water-container, a gas-receiving chamber, and a chamber communicating with the burner, of a cock for controlling the flow of gas from the receiving-chamber into the burner and for controlling 100 the admission of air into the water-container. 95

8. In an acetylene-gas generator, the combination with the water-container, a gas-receiving chamber, and a chamber communicating with the burner, of a cock having two 105 channels, one for controlling communication between the receiving-chamber and the chamber connecting with the burner and the other for controlling communication between the outside air and the water-container, said channels being so related as to cut off communication between the water-container and the outside air except when full communication is established between the gas-receiving chamber and the chamber connecting with the 110 burner. 115

9. In an acetylene-gas generator, the combination with the water-container, a chamber connecting with the burner, a gas-receiving chamber, and a carbid-container, of a cock for controlling the flow of gas from the receiving-chamber into the burner and for controlling the admission of air into the water-container, and means operatively connected with the cock for raising and lowering the 120 carbid-container. 125

10. In an acetylene-gas generator, the combination with the water-container, a chamber communicating with the burner, a gas-receiving chamber and a carbid-container, of a 130

cock having two channels, one for controlling communication between the receiving-chamber and the chamber connecting with the burner, and the other for controlling communication between the outside air and the water-container, said channels being so related as to cut off communication between the water-container and the outside air except when full communication is established between the gas-receiving chamber and the chamber connecting with the burner, and means operatively connected with the cock for lowering the carbid-container when full communication is established between the receiving-chamber and the chamber connected with the burner.

11. In an acetylene-gas generator, the combination with a cock for controlling the supply of gas to the burner and for establishing communication between the outside air and the interior of the generator, a carbid-container, a raising and lowering device for the container, said device comprising a vertically-movable rod, means for lifting the rod operated by the cock and engaging one end of the rod, and means on the other end of the rod to engage the container.

12. In an acetylene-gas generator, the combination of a carbid-container, a grate for supporting the carbid, a yoke beneath the grate through which the grate and carbid may be inserted into the container, and a curved cross-bar pivoted in said yoke and movable into and out of the path of said grate.

13. In an acetylene-gas generator, the combination of a carbid-container, a tube and grate for holding the carbid and movable within said container, a yoke beneath the container through which the tube and grate may be inserted into the container and by which they may be raised in the container, and a curved cross-bar pivoted in said yoke and movable into and out of the path of said tube and grate.

14. In an acetylene-gas generator, means operating automatically when the generator is tilted or upset for raising the carbid from the water.

15. In an acetylene-gas generator, a movable rod extending through the bottom thereof and adapted to be extended upon the moving of the lamp from its support, and means actuated by the movement of said rod to seal the carbid from the water.

16. In an acetylene-gas generator, means for raising the carbid from the water and a device to actuate said means operating automatically when the generator is tilted or upset.

17. In an acetylene-gas generator, means for preventing the contact of the water and carbid, a device to actuate said means, and an automatically-actuated member extending through the exterior of the generator to which said device is operatively connected, so that when the generator is tilted or upset said mem-

ber will be extended and will operate the device.

18. In an acetylene-gas generator, means for closing the carbid-chamber, a device to actuate said means, a spring-actuated rod extending through the bottom of the generator to which said device is connected, and a free disk on the bottom of the generator and secured to the rod, whereby when the generator is tilted or upset the disk will move away from the bottom and the rod will be extended through the bottom and will operate the device.

19. In an acetylene-gas generator, the combination with a carbid-container, of a plug adapted to fit into the end of said container, a spring normally under compression, and connections adapted to communicate the energy of the spring to the plug whereby the plug upon the expansion of the spring will be moved to close the end of the container.

20. In an acetylene-gas generator, the combination with a carbid-container, of a plug adapted to fit into the end of said chamber, a free disk upon which the generator normally rests, a spring normally confined between the generator and disk, and connections adapted to communicate the energy of the spring to the plug whereby the plug upon the expansion of the spring will be moved to close the end of the container.

21. In an acetylene-gas generator, the combination of a carbid-container, a plug adapted to fit into the end of said chamber, a free disk upon which the generator normally rests, a spring normally confined between the generator and disk, a rod upon the disk, a vertically-movable frame connected with the rod, a lever pivoted to the frame and engaging the plug to communicate the force of the spring to the plug whereby the plug upon the expansion of the spring will be moved to close the end of the container.

22. In an acetylene-gas generator, the combination with the water-container and an air-inlet pipe in said water-container, of a valve having a valve-seat in said pipe, and a plug in said valve-seat adapted upon the entrance of water into the valve-seat to float to prevent the backing out of the water in the container in case of a rise of pressure therein.

23. In an acetylene-gas generator, the combination with the water-container, of a valve having a valve-seat communicating with said container and the outer air, a heavy ball in said valve-seat, and a relatively light plug resting therein on said ball and adapted, upon the upsetting of the generator to be moved by said ball to cut off communication between the container and the outside air.

24. In an acetylene-gas generator, means for preventing the contact of the water and carbid, a device to actuate said means, and a spring-actuated rod extending through the bottom of the generator to which said device

is operatively connected, so that when the generator is tilted or upset said rod will be extended and will operate the device.

25. In an acetylene-gas generator, means for withdrawing the carbid from the water and sealing the carbid against contact with the water, said means operating automatically when the generator is tilted or upset.

This specification signed and witnessed this 2d day of April, A. D. 1903.
